(57) CLAIM

The ornamental design for a toothbrush head, as shown and described.

DESCRIPTION

FIG. 1 is a perspective view of a first embodiment of a toothbrush head;

FIG. 2 is a front view thereof;

FIG. 3 is a right side view thereof;

FIG. 4 is a rear view thereof;

FIG. 5 is a left side view thereof;

FIG. 6 is a top plan view thereof;

FIG. 7 is a bottom view thereof.

FIG. 8 is a perspective view of a second embodiment of a toothbrush head;

FIG. 9 is a front view thereof;

FIG. 10 is a right side view thereof;

FIG. 11 is a rear view thereof;

FIG. 12 is a left side view thereof;

FIG. 13 is a top plan view thereof; and,

FIG. 14 is a bottom view thereof.

The broken lines illustrate portions of the toothbrush head that form no part of the claimed design.

1 Claim, 8 Drawing Sheets

Related U.S. Application Data

29/654,969, filed on Jun. 28, 2018, now Pat. No. Des. 902,600, which is a division of application No. 29/561,313, filed on Apr. 14, 2016, now Pat. No. Des. 824,174.
